CIRCUIT BREAKER AND IGNITION
TIMING DEVICEWalter Ochsenbein, Bern, Switzerland, assignor
to Hasler A.-G. Werke für Telephonie und
Präzisionsmechanik, Bern, SwitzerlandApplication April 21, 1942, Serial No. 439,878.
In Switzerland January 3, 1941

8 Claims. (Cl. 123—117)

The present invention relates to a circuit breaker and ignition timing device for internal combustion engines.

One object of the present invention is to provide means whereby the circuit breaker contacts of a normally-cam-operated circuit breaker device are moved to and retained in a permanently open position independently of the cam action whenever the rotary speed of the magneto produces a sufficiently high voltage in the secondary circuit of the circuit breaker to permit generation of an ignition spark without alternate opening and closing of the primary circuit.

Another object of the invention is to preserve the frictionally cooperating surfaces of the breaker contacts and of the control cam, respectively, by the provision of means for lifting the breaker contacts entirely off the control cam, when the voltage produced by the magneto in the secondary circuit of the circuit breaker is sufficiently high for the generation of ignition sparks without intermittent closing of the primary circuit.

A still further object of the invention is to provide, in combination with a circuit breaker of the type mentioned, means to readjust the timing of the sparking device automatically upon setting of the breaker contacts to their permanently open positions so as to compensate for the more rapid generation of the sparking voltage obtained in this manner.

These and other objects which will appear more clearly as the description proceeds, are accomplished by the arrangement and combination of elements set forth in the following detailed description, defined in the appended claims and illustratively exemplified in the appended drawing, the single figure of which shows partly in elevation and partly in section a circuit breaker arrangement according to the invention including means for a readjustment of the spark timing.

A lever 4 is mounted rotatably on the shaft 1 of a cam disc 3 which controls two circuit breaker levers 2. Lever 4 carries at its ends two laterally projecting bosses 5 and is connected by a rod 6 to a piston 7 which is slidable in a cylinder 8 and urged upwards in said cylinder by a spring 9. The space in the cylinder 8 above the piston 7 communicates through a conduit 10 with an operator controlled three way valve 11 to which are connected a return conduit 12 leading to an oil tank. In the illustrated position of valve 11, the oil pump is connected to the conduits 10 and 14. The valve 11 may be turned through 90° in a clockwise direction to connect the conduits 10 and 14 to the return conduit 12. The

conduit 14 leads to a hydraulically operated device for adjusting the spark timing.

In the drawing, this device is shown, by way of example, as a hydraulic brake acting on a portion of the magneto coupling 22. The latter comprises a cup-like coupling portion 23 keyed to the shaft 24 of a multiple magneto (not shown). The second coupling portion 25 is formed as a cover and rotatably seated with its hub 25a upon the hub 23a of the portion 23. Both portions 23 and 25 together form a housing for a spiral spring 26, the inner end of which is connected to the hub 25a of the coupling portion 25 while its outer end is secured to the inner peripheral wall surface of the coupling portion 23 by means of a rivet 26a. The cylindrical flange of the coupling portion 23 is provided with upstanding projections 23b and the coupling portion 25 carries radial projections 25b meshing with some play with the projections 23b so that the two coupling portions can be angularly displaced relative to each other to a predetermined extent. Normally, they are urged by the spring 26 into a position in which the rear surface of each projection 25b contacts the front surface of the next following projection 23b. A gear wheel 27 is secured by means of screws 28 to brackets 29 integral with the coupling portion 25, said gear wheel being adapted to be geared at a suitable ratio to the crankshaft of the engine.

When the gear wheel 27 is rotated at slow engine speeds, the coupling portion 23 is retarded relative to the coupling portion 25 by the attraction of the multipole magneto and, the tension of the spring 26 is increased until the portion 23 is positively advanced by the front surface of each projection 25b acting upon the rear surface of the next preceding projection 23b. At high engine speeds, the magneto attraction becomes relatively negligible and the spring 26 tends to hold the portion 23 permanently in its original position relative to the coupling portion 25 which position corresponds to an early spark timing.

In order to produce a late ignition at engine speeds exceeding a predetermined magnitude, the brake 21 is operated. This brake comprises a brake head 30 supported in reach of the outer flange of the coupling portion 23 by a piston 31 fitted slidably in a cylinder 32 and held by a spring 33 normally in a position in which the brake is inoperative. The brake cylinder 32 is provided with a port 34 connected to the conduit 14 for the admission of oil in the rear of the piston 31 to cause axial displacement of the lat-

ter against the force of the spring 33 in order to operate the brake pressure conduit 13 connected to an oil pump and a conduit 14, a valve 15 in the conduit 14 is operatively connected by means of a leverage 16 to a rod 17 slidably guided in a longitudinal direction at right angles to rod 6. Rod 17 carries a follower head 19 urged against reach of a cam 18 provided on the rod 6 by a spring 20.

When the engine is at rest, rod 6 with piston 7 is in its upper end position so that the bosses 5 of lever 4 do not interfere with the movement of the circuit-breaker-levers 2 which are then controlled by the cam disk 3. When the speed of the motor has reached a certain value, rod 6 with cam 18 is pressed downwards by a pressure on the piston 7 depending upon the number of revolutions of the engine. Cam 18 touches with its lower bevel edge the bevel edge of follower head 19. The inclination of said bevel edges of cam 18 and of head 19 and the tension of the adjustable spring 20 are so chosen, that rod 6 removes rod 17 only at a certain value of the pressure on piston 7 the follower head 19 is caused to ride up the entire bevel surface of cam 18. As soon, however, as this pressure value is exceeded and the tip of follower head 19 rests against the surface of cam 18 extending parallel to the longitudinal axis of rod 6, the resistance of the follower 19 against the downward travel of cam 18 and rod 6 drops suddenly almost to zero and the rod 6 is jerked downwards against the action of spring 9 into its lower end position which is defined by the contact of piston 7 with a shoulder 8' of cylinder 8. By this sudden downwards movement of rod 6, lever 4 is shifted abruptly from its inoperative position, and the bosses 5 push the circuit breaker levers 2 instantly out of the path of cam disk 3. A sufficiently high sparking voltage is reached without operation of the circuit breaker at the high speed of the engine producing the predetermined oil pressure value, and the sparking will, thus, be continued after the sudden cutting out of the circuit breaking levers. When the follower head is displaced toward the right, the rod 17 turns the valve 15 by means of the leverage 16, and, at the precise moment when the rod 6 is jerked downwardly, the valve 15 has assumed its open position so that the oil under pressure can flow into the brake cylinder 32 and cause the brake to act on the coupling portion 23. The latter will thus be angularly displaced from its position with respect to the coupling portion 25 into which it is urged by the spring 26. This angular displacement, in turn, effects a retardation of the ignition compensating for the more rapid generation of sparking voltage in the magneto by the free development of the magnetic field as compared to its operation with an alternately open and closed circuit breaker.

If, for any reason it should be desirable at a high engine speed to have the circuit breakers operate, cock 11 is turned from the shown position clockwise through 90° whereupon the oil will be pressed by the piston 7 under the effect of spring 9 from cylinder 8 into the oil tank and lever 4 is swung back by rod 6 to free circuit breaker levers.

What I claim is:

1. A circuit breaker arrangement for the ignition mechanism of an internal combustion engine, comprising in combination with a cam disc and at least one normally closed breaker contact arranged to be intermittently opened by said

cam disc, a rockable lever capable of assuming an operative position in which a cam portion of said lever cooperates with said breaker contact to hold the same in a permanently open position beyond the reach of said cam disc and an inoperative position in which the lever does not interfere with the control action of the cam disc on the breaker contact, means urging said lever towards said inoperative position, and means for moving said lever from said inoperative to said operative position when the engine speed reaches the value at which an intermittent opening and closing of the circuit breaker is no longer required for the generation of a sparking voltage.

2. A circuit breaker arrangement, as claimed in claim 1, in which said lever is rockable about the axis of rotation of said cam disc.

3. A circuit breaker arrangement, as claimed in claim 1, in which said means for moving said lever includes a first cam displaceable in one direction in dependence upon a force which is a function of the engine speed, said cam having a bevelled nose portion and rearwardly of said nose portion a face extending substantially parallel to the direction of its movement, a second bevelled cam displaceable in a direction at substantially right angles to the direction of movement of said first cam, and a spring urging said second cam against said first cam.

4. A circuit breaker arrangement, as claimed in claim 1, including means operative when the engine speed reaches said value to retard the spark timing so as to compensate for the more rapid generation of sparking voltage.

5. In an internal combustion engine having an engine driven oil pump and an ignition mechanism including a circuit breaker containing an engine driven cam disc and at least one normally closed breaker contact arranged to be intermittently opened by said cam disc, the combination of a rockable lever capable of assuming an operative position in which a cam portion of said lever cooperates with said breaker contact to hold the same in a permanently open position beyond the reach of said cam disc and an inoperative position in which the lever does not interfere with the control action of the cam disc on the breaker contact, a closed cylinder having a lower part and a head portion, a conductor connecting the head portion of said cylinder with said oil pump, a piston slidable in said lower part of said cylinder, a spring in said cylinder below said piston to urge the latter towards the head portion of said cylinder, and a piston rod extending through the bottom of said cylinder and having its free end hinged to said lever, so as to move the latter from its inoperative to its operative position when the oil pressure acting on said piston reaches a value corresponding to the engine speed at which an intermittent opening and closing of the circuit breaker is no longer required for the generation of a sparking voltage.

6. In a combination, as claimed in claim 5, an oil outlet conduit and operator controlled means for disconnecting said cylinder head portion from said oil pump and connecting it to said oil outlet conduit.

7. In a combination, as claimed in claim 5, a hydraulically operated mechanism for retarding the spark timing, a conduit connecting said mechanism with said oil pump, a normally closed valve in said conduit, and means for opening said valve when the engine speed reaches said value.

8. In an internal combustion engine having

an engine driven oil pump and an ignition mechanism including a hydraulically operated device for retarding the spark timing and a circuit breaker containing an engine driven cam disc and at least one normally closed breaker contact arranged to be intermittently opened by said cam disc, the combination of a rockable lever capable of assuming an operative position in which a cam portion of said lever cooperates with said breaker contact to hold the same in a permanently open position beyond the reach of said cam disc and an inoperative position in which the lever does not interfere with the control action of the cam disc on the breaker contact, a closed cylinder having a lower part and a head portion, a conductor connecting the head portion of said cylinder with said oil pump, a piston slideable in said lower part of said cylinder, a spring in said cylinder below said piston to urge the latter towards the head portion of said cylinder, a piston rod extending through the bottom of said cylinder and having its free end hinged to said lever to hold the latter in its inoperative position as long as said piston is near its upper position in said cylinder and to move the lever from its inoperative to its operative position when the piston is displaced under the oil pressure to its lowermost position in said cylinder, a conduit connecting the spark timing retarding device with said oil

5 pump, a valve in said conduit, a valve rod displaceable along its own longitudinal axis in a direction at right angles to the direction of movement of said piston rod, a first cam on said piston rod, said first cam having a bevelled nose portion and, rearwardly of said nose portion, a face extending substantially parallel to the movement of said piston rod, a second bevelled cam on the free end of said valve rod and a valve rod spring 10 holding said valve rod normally in a position in which said second cam extends into the path of said first cam and said valve is closed, the bevel surfaces of said cams the power of said valve rod spring and the connection between said valve rod and valve being so chosen and arranged that the oil pressure on said piston acts on the co-operating bevelled cam faces to shift the second cam out of the path of the first cam at the exact moment when the oil pressure reaches a value 15 corresponding to the engine speed at which an intermittent opening and closing of the circuit breaker is no longer required for the generation of a sparking voltage, and said valve is opened by said valve rod at precisely the same moment, 20 whereby the lever is shifted abruptly to its operative position and simultaneously the spark timing is sufficiently retarded to compensate for the more rapid generation of the sparking voltage.
